UNITED STATES PATENT OFFICE.

PERCY H. THOMAS, OF UPPER MONTCLAIR, NEW JERSEY.

ELECTRIC INSULATOR.

1,250,387.

Specification of Letters Patent. Patented Dec. 18, 1917.

Application filed May 16, 1913. Serial No. 767,995.

To all whom it may concern:

Be it known that I, PERCY H. THOMAS, a citizen of the United States, and resident of Upper Montclair, county of Essex, State of New Jersey, have invented certain new and useful Improvements in Electric Insulators, of which the following is a specification.

My invention relates to insulators for high tension electric lines, such as power transmission lines. More particularly my insulator is of the suspension type and is adapted to extra-high tension service.

It is found that the size and cost of high tension insulators, such as are used for high transmission voltages, become excessive as the voltage is raised, and that when several insulators are used in a string to support the line, that the potential of the line is not divided equally between them. As a result after a certain number of units have been put in one string little gain is found in adding more units. My invention provides an insulator which is relatively free from these defects and is at the same time cheaper and easier to construct and more convenient in form. I also utilize a novel mechanical principle in insulators of this type, in that I may rely on vitreous material in tension.

I prefer to use insulating material for the main body of my insulator of porcelain, glass or other vitreous material which has a very high dielectric quality and is capable of being obtained of great uniformity and high quality. This material has certain mechanical limitations, however, due to manipulation in manufacture so that many desirable forms and methods of construction cannot be used. The insulators here shown, however, are well adapted to the characteristics of the materials available for high tension insulators.

The ability of any particular insulating device to stand electric strain is known to depend far more on the distribution of the electric stress in the dielectric or insulating material than on the thickness of the dielectric and I have taken advantage of this principle in my insulator. I have also used such forms of construction whereby a larger thickness of insulating material is practicable than in the ordinary insulator constructions.

I also provide a form favorable for resisting the effects of heavy rain or mist which tend to cause a breakdown of an insulator. I provide an insulator that will have a rela-

tively great mechanical strength as well as good electrical characteristics.

My invention will be understood by reference to the accompanying drawings, in which—

Figure 1 is a longitudinal central sectional view of an insulator embodying my invention;

Fig. 2 is a sectional view on line 2—2 of Fig. 1;

Figs. 3 and 4 are similar sectional views of two modifications of Fig. 1;

Fig. 5 is a plan view of a detail of Fig. 4, portions being broken away;

Fig. 6 is a sectional view of a string suspension insulator conforming generally with the aforesaid figures;

Fig. 7 is a sectional view of a modified type of suspension, comprising rigidly connected units;

Fig. 8 is a cross section on the line 8—8 of Fig. 7; and

Fig. 9 is a vertical sectional view of another modification of Fig. 1.

In the form of my invention shown in Fig. 1 the two U-shaped pieces 22, 23, are provided with large overhanging ends as shown, which tend to give a flat electric field between the top and bottom of the insulator. There is of course a much more concentrated field between the U-shaped pieces 22, 23, within the porcelain 19 but this is not a stress in air and the porcelain itself must be punctured for a break to occur at this point. These enlarged conducting portions serve particularly to control the electric field in the air at the ends of the porcelain piece, and thus prevent a premature breakdown of the air locally. They further serve to make the natural direction of the lines of electric force along this surface more nearly parallel to the center line between the terminals. I prefer to so shape this overhanging portion and the surface of the porcelain itself that no lines of electric force shall enter or leave the porcelain surface, or at least to approximate this condition.

In Fig. 1 I have shown the main body of the insulator, the porcelain piece at 19, the two overhanging metal portions at 20 and 21, the U-shaped pieces at 22 and 23.

In Figs. 3 and 4, I show certain modifications of the insulator of Fig. 1. I use porcelain bodies with overhanging metal portions above and below, but in these in-

sulators I rely on the tensile strength of the porcelain to carry the load of the insulator. I am aware that this has not been attempted heretofore in line insulators but with the precautions which I take in my designs this plan is not only feasible but desirable. This design permits of a much greater insulation strength, of a better control of the distribution of the electric field and a simpler mechanical construction.

In Fig. 3, 24 is the porcelain piece with the recesses at top and the bottom respectively. In these recesses are pipes or metal cylinders fitting rather closely and cemented to the porcelain with Portland or other cement. These pipes carry plugs 27 and 28 which are provided with hooks or rings as may be desired. At the top and bottom of the insulator and carried if desired on the pipes are overhanging conducting pieces 25 and 26, which serve to control the form of the electric field at the surface of the porcelain as described in connection with Fig. 1. At 31, I show a ring or rib for breaking up any tendency for water to form streams on the surface of the porcelain and to increase the creepage surface. If desired there may be used more of these ribs at various points on the surface of the porcelain.

Fig. 4 is like Fig. 3, except that the porcelain piece 34 is larger in size and is furnished with larger recesses, which are formed to carry porcelain or other insulating cups cemented into the recesses, as shown at 37 and 41. Within these cups are cemented pipes as before, shown at 38 and 40, carrying plugs 45 and 46, screwed or otherwise fastened into the pipes 38 and 40. Fig. 4 as well as Fig. 3 shows a flat screw thread on the inside of the porcelain surface which is to make the cement take a better hold thereon, see 39, 39, in Fig. 4. At 35 and 36 are shown plates constituting the field controlling conductors at the top and bottom of the porcelain. The porcelain surface here shown is curved at 44 to conform more nearly to the lines of electric force in the air. A rib 43 is used, similar to the rib 31 of Fig. 3.

With the type of insulator shown in Figs. 3 and 4, it is clear that the porcelain barriers 32 and 42 between the recesses in the porcelain can be made as thick as desired and thus may withstand very high potential strains. Similarly the use of the cups of Fig. 4 again greatly increases the insulation strength of the insulator and has the advantage that the cups may be made separately and may be tested separately and then assembled and cemented, thus insuring more uniform material and avoiding the use of any very thick material.

In Fig. 5 is shown the top view of the porcelain cups of Fig. 4 with the major portion of the porcelain piece 34 broken away.

In Fig. 6 is shown a train of insulators of the general type of Fig. 3, but having wings or umbrella plates to assist in securing an even distribution of potential between the several units of the string. It is well known that, since in a string of insulators, all the charging current that must satisfy the ground capacity of the several insulators of the string will have to pass through or over the line unit, this unit will tend to take more than its share of the potential and so one down the line, the last insulator having less stress than any of the others. I overcome this condition by providing a means of giving more capacity to the insulator units nearer the line, to compensate for the greater charging current flowing over such insulators. Of course, I can similarly increase the capacity of any particular insulator unit when desired.

I accomplish this desirable result by using plates or umbrella pieces, graded in size and attached to the metal caps above and below the appropriate insulators. These pieces may be detachable and should be so shaped as to shed the rain. Thus a string of insulators may be made up and then when installed the caps may be added as is necessary to obtain this correct balance of potential.

The porcelain pieces of the individual insulators of Fig. 6 are shown at 47, the plugs or pipe pieces at 48, the top and bottom conductors at 49 and the umbrella pieces at 50, graded to give progressively greater capacities toward the insulator nearer the conductor 51. If it be desired to grade the capacity in the opposite direction this can, of course, be done by reversing the order of the umbrella pieces. The pieces 48 are shown having rounded terminals at the central portions of the porcelain, to give a more uniform electric field.

Figs. 7 and 8 show a modification of the insulator of Fig. 3, where instead of using a single pipe piece to carry the load a number of smaller pieces, extensions, or rods are used arranged to get a better hold on the porcelain and yet to form, electrically speaking, substantially a single similar conductor or electrode. By this construction thinner porcelain walls are obtained, which is an advantage from a manufacturing point of view. This insulator is shown as made up of two parts, semi-rigidly fastened together. Other numbers of units than the two shown may be used. The porcelain pieces are shown at 52, the rods used for carrying the load and forming the electric field are shown at 53 and the metal caps at the top and bottom of the porcelain pieces are shown at 54, 58, 59 and 60. The piece 56 carries the piece 54 and the other supporting pieces are fitted together mechanically to give strength and to shed the rain as is shown. There are ribs

or ridges 55 and 57 on the pieces 54 and 58 which are filled with cement and serve to hold the porcelain from breaking out under strain. Similar means may be used with the 5 other porcelains in this and in other figures. I sometimes prefer to extend the center rod 53 to give the effect of a somewhat rounded terminal at the central portion of the porcelain, similar to pieces 48 of Fig. 6, as above 10 described to give a somewhat more uniform electric field. This train of insulators will swing as a unit and not each unit on the other as may be the case when the connection between units is flexible. The piece 61 15 carries the line conductor.

The insulator of Fig. 9 is like that of Fig. 1, except that the porcelain piece 62 is not round in cross section, but is flattened and that the rods or holding pieces are more 20 numerous and are of different lengths to utilize the compressive strength of the porcelain. The short rods are shown at 65 and the long rods at 64. The porcelain piece is 62 and the two metal overhanging pieces 25 are shown at 63. These overhanging pieces will act as a protection from the weather both in this and the other structures where they are used.

It will be understood that the various 30 forms of insulators and other devices that I have shown in connection with any one figure may be used with the other forms wherever appropriate and that I do not limit my invention to the particular constructions shown but that any other embodiments of the same ideas, obtaining substantially the same results by equivalent means come within its scope.

What I wish to secure is in part the 40 design of an insulator to secure a relatively uniform distribution of electric field at the critical points, which will greatly increase the voltage that the insulator will stand and to get simple mechanical forms relying in 45 some instances on the tensile strength of porcelain. With the relative short and thick shapes recommended these insulators will be found reliable.

A suitable distribution of the electrostatic 50 field in the portion of the main body of the porcelain or other insulating material lying between the metal attachment pieces is important, as well as in the air surrounding the insulating member, since this will provide greater reliability with a given minimum thickness of porcelain, or a thinner material as may be appropriate. This control 55 of the field within the porcelain may be attained by properly shaping the opposing 60 faces of the metallic attachment pieces. For example, by making them approximately flat and parallel as in Figs. 3 and 4, or as in Figs. 7 and 8, where there are a plurality

of opposing faces on each attachment piece, by locating the several faces of each attachment piece on a mathematical surface, approximately a plane surface and generally parallel to the similar surface containing the faces of the second attachment pieces.

The distribution of these electrostatic stresses in the porcelain or other insulating material can be made more perfect by making the above mentioned plane surfaces slightly convex toward each other, as shown 75 in Figs. 6 and 9 or in Figs. 7 and 8, where the central metallic figures may be advanced slightly over the outer figures, as described above.

I claim as my invention.

1. In a high tension line insulator, a load carrying tension member of vitreous material, having a plurality of recesses on opposite faces, stress taking members entering said recesses, means for distributing the mechanical stress from the stress taking members over the surfaces of said recesses and thin walls for that portion of the tension member adjacent to the stress taking members, whereby the mechanical forces are favorably distributed.

2. In a line insulator, a porcelain tension member carrying the load of the insulator, having its end portions disposed in the form of walls or partitions thin relative to the 95 stress receiving surface of the member and forming recesses in the said tension member, metal stress bearing members secured in said recesses, whereby mechanical stress may be favorably distributed throughout the material of the tension member.

3. In a line insulator, a porcelain tension member carrying the load of the insulator, having its end portions disposed in the form of walls or partitions thin relative to the 105 stress receiving surface of the member and forming recesses in the said tension member, metal stress bearing members secured in said recesses, whereby mechanical stress may be favorably distributed throughout the material of the tension member, the metal members attached to the respective ends of the porcelain tension member being disposed with their opposed faces located in a plane surface lying generally parallel, whereby 110 the electrostatic stresses in the porcelain between the opposed faces are favorably distributed.

Signed at New York, in the county of New York and State of New York, this 15 120 day of May, A. D. 1913.
